United States Patent Office

Des. 195,115
Patented Apr. 30, 1963

195,115

TOOTHBRUSH OR SIMILAR ARTICLE

Edgar A. Phaneuf, Southborough, Mass., assignor to General Electric Company, a corporation of New York

Filed Sept. 7, 1961, Ser. No. 66,631

Term of patent 14 years

(Cl. D9—2)

Fig. 3.

Fig. 4.

Fig. 5.

Fig. 6.

Fig. 7.

FIG. 1 is a fragmentary top perspective view of a toothbrush or similar article embodying my new design;

FIG. 2 is a fragmentary bottom perspective view thereof;

FIG. 3 is a fragmentary top plan view thereof;

FIG. 4 is a fragmentary side elevational view thereof;

FIG. 5 is a fragmentary cross-sectional view thereof;

FIG. 6 is a fragmentary front elevational view thereof; and

FIG. 7 is a perspective view thereof on a reduced scale.

The essential features of my design reside in the portions shown in full lines.

Portions of the article are broken away in FIGS. 1, 2, 3, 4, 5 and 6 for the convenience of illustration.

I claim:

The ornamental design for a toothbrush or similar article, substantially as shown and described.
